FRED J. TRIMBLE, OF MAYWOOD, CALIFORNIA

GRINDING WHEEL GUARD

Application filed September 30, 1931. Serial No. 566,082.

The present invention relates to a grinding wheel guard and has for its primary object to provide, in a manner as hereinafter set forth, a device of this character embodying a novel construction, combination and arrangement of parts through the medium of which flying particles which may be thrown out by centrifugal force will be arrested, thereby preventing possible injury to the person using the wheel.

Another important object of the invention is to provide a grinding wheel guard of the character described which is adapted to enclose a major portion of the wheel and which includes novel means for adjustment through the medium of which as much of the wheel as may be desired may be exposed.

A further important object of the invention is to provide a grinding wheel guard of the aforementioned character which may be expeditiously adjusted to fit various sizes of grinding wheels and also to accurately fit a grinding wheel as it is worn away.

Other objects of the invention are to provide a grinding wheel guard which will be simple in construction, strong, durable, efficient and reliable in use and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in front elevation of a guard in accordance with the present invention.

Figure 2 is a view in side elevation thereof.

Figure 3 is a view in vertical section taken substantially on the line 3—3 of Figure 1.

Figure 4 is a view in vertical cross section taken substantially on the line 4—4 of Figure 2.

Referring now to the drawings in detail, it will be seen that the reference numeral 1 designates a supporting stand upon which an electric motor 2 is secured through the medium of the bolts 3 and 4. The bolts 4 are also

utilized to secure a supporting bracket 5 in position, said bracket having a downwardly offset outer portion and having the upper side of its free end portion concave, as at 6.

A substantially segmental housing designated generally by the reference numeral 7 is adjustably mounted on the bracket 5. The housing 7 comprises an inner wall 8 with which the peripheral wall 9 is formed integrally. The housing 7 further comprises an outer wall 10 which is removable and which is secured in position by the angle clips 11 the legs of which are apertured for the passage of screws 12 which are threaded into said outer wall 10 and the peripheral wall 9. The outer wall 10 of the housing 7 is formed with an outwardly pressed central portion 13 providing a chamber 14. The inner wall 8 is provided with a centrally disposed opening 15 for the passage into the housing of the motor shaft 16 upon which the grinding wheel 17 is secured by suitable means including a retaining nut 18 which is threaded on the free end portion of the motor shaft 16. The chamber 14 accommodates said free end portion of the motor shaft 16 and the nut 18.

The peripheral wall 9 of the housing 7 seats in the concavity 6 of the bracket 5 and has in its lower portion a circumferentially extending slot 19 for the passage of a clamping bolt 20. The head of the bolt 20 is engaged with the inner periphery of the wall 9 of the housing. The bolt 20 passes through the slot 19 and through an opening provided therefor in the free end portion of the bracket 5 and has threaded thereon a winged nut 21. A lock washer 22 is mounted on the bolt 20 between the winged nut 21 and the bracket 5.

As will be seen a portion of the wheel is exposed by the cut away portion of the substantially segmental housing 7. The area of the wheel which is exposed may be regulated as desired by loosening the clamping bolt 20 and rotating or tilting the housing 7 on the bracket 5, as indicated in broken lines in Figure 3 of the drawing. Obviously when the housing 7 is shifted to bring one end of the slot 19 closer to the bolt 20, the exposed portion of the wheel 17 will be increased and when the housing 7 is shifted to bring the other end

of the slot 19 closer to the bolt 20 the area of the wheel 17 which is exposed will be decreased. The reference numeral 23 designates a section conduit which is connected to a lower, rear portion of the housing 7 for carrying away dust and loose particles. In-turned flanges 24 are provided on the ends of the peripheral wall 9 of the housing 7. The reference numeral 25 designates angular side guard plates which are disposed closely adjacent the side faces of the wheel 17. The guard plates 25 are adjustably mounted on the side walls 8 and 10 of the housing 7 in the opening of said housing through which the wheel 17 projects and for adjustment toward and away from said wheel through the medium of the angular clips 26 which may be secured on the housing by screws 27. The side guard plates 25 are provided with transverse slots 28 for the passage of the screws 29 which are threaded into the angle clips 26. Thus, by loosening the screws 29, the guard plates 25 may be adjusted laterally toward or away from the grinding wheel 17, as indicated in broken lines in Figure 1 of the drawing.

The reference numeral 30 designates transversely extending upper and lower guard plates which are substantially flat and which have one edge disposed closely adjacent the periphery of the wheel 17. The upper and lower guard plates 30 overlap the upper and lower end portions of the side guard plates 25 and have their end portions provided with the vertically extending slots 31 which communicate with the uppermost and lowermost transversely extending slots 28 of the guard plates 25. The uppermost and lowermost of the screws 29 are utilized for adjustably securing the upper and lower guard plates 30 in position for adjustment toward or away from the periphery of the wheel 17, said screws, of course, being operable in the slots 31. As best seen in Figure 3 of the drawing, the upper and lower portions of the side guard plates 25 abut the flanges 24 of the housing 7.

It is believed that the many advantages of a guard in accordance with this invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A grinding wheel guard comprising a bracket, a substantially segmental housing mounted on the bracket, the cut-away portion of the housing being open, the wheel being operable in the housing and projecting through the opening, guard plates shiftably mounted on the housing for lateral adjustment toward and away from the side faces

of the wheel, and guard plates shiftably mounted on the housing for adjustment toward and away from the periphery of the wheel.

2. A grinding wheel guard comprising a bracket having a free end portion provided with an arcuate recess, a substantially segmental housing adjustably mounted on the bracket and seated in the recess, the cut-away portion of the housing being open, the wheel being operable in the housing and projecting through the opening, the peripheral portion of the housing which is engaged with the bracket having a circumferentially extending slot therein, a headed bolt engaged with the housing and extending through the slot and the bracket, and a nut threaded on the bolt for frictionally clamping the housing in adjusted position on the bracket.

3. A grinding wheel guard comprising a substantially segmental housing, a cut-away portion of said housing being open, the wheel being operable in the housing and projecting through the opening therein, substantially vertically disposed angular guard plates shiftably mounted on the housing over the opening therein for lateral adjustment toward and away from the side faces of the wheel, and transversely extending guard plates shiftably mounted on the end portions of the first named guard plates for adjustment toward and away from the periphery of the wheel.

4. A grinding wheel guard comprising a substantially segmental housing, a cut-away portion of said housing being open, the wheel being operable in the housing and projecting through the opening therein, substantially vertically disposed angular guard plates shiftably mounted on the housing over the opening therein for lateral adjustment toward and away from the side faces of the wheel, and transversely extending guard plates shiftably mounted on the end portions of the first named guard plates for adjustment toward and away from the periphery of the wheel, angle clips rigidly mounted on the housing adjacent the opening therein, the first named guard plates having transversely extending slots therein, the second named guard plates having substantially vertically extending slots therein, and securing elements passing through the slots and threadedly engaged with the angle clips for securing the guard plates in adjusted position on the housing.

In testimony whereof I affix my signature.

FRED J. TRIMBLE.
